UNITED STATES PATENT OFFICE

2,000,167

LIQUID DISPENSER

James Forman, Astoria, Long Island, N. Y., assignor to Florence B. Bohack, New York, N. Y., doing business under the name of Progress Supply Company

Application February 13, 1934, Serial No. 711,005

4 Claims. (Cl. 221—16)

This invention relates generally to liquid containers and dispensers and more particularly to such devices adapted for use with floor mops and the like.

5 It is an object of my invention to provide such a container and dispenser with means for controlling the discharge of the liquid.

Another object is to provide a device of this kind with means for readily attaching and detaching it from the handle of a mop or the like.

10 A further object is to provide a liquid container and dispenser that is positive in operation.

Other objects and advantages of my improved device will be apparent from the description thereof taken in connection with the accompanying drawing in which—

15 Figure 1 is a side elevation of a mop having a liquid container and dispenser embodying my invention mounted on the handle thereof.

20 Figure 2 is a side elevation of a different type of mop with my improved container and dispenser mounted on the handle thereof.

25 Figure 3 is an enlarged central vertical section through my improved container and dispenser.

Figure 4 is an enlarged front elevation of a bracket for the handle for supporting the container and dispenser.

30 Figure 5 is a top plan view of the bracket shown in Figure 4.

Figure 6 is a detail view showing the cap on the bottom of the container and dispenser.

35 Figure 7 is a sectional view of the support for the valve shaft taken on the line 7—7 of Figure 3.

Referring to the drawing, an ordinary type 40 of commercial mop is shown in Figure 1 for oiling floors and the like. The mop includes a handle 9 pivotally connected to a mop head 10.

This mop head comprises a frame 11 from which mopping or oiling material 10a is suspended. A horizontal plate 12 secures the material 10a to the frame. This plate is provided

45 with openings to permit liquid such as oil to seep downwardly to the material below. The means of connection between the handle 9 and the mop head 10 is shown as a split sleeve 13, the bottom end of which is pivotally mounted

50 on a hinge pin 14 passing between the bifurcated ends of the frame 11. A wing nut 15 removably clamps the handle to the sleeve.

55 My improved liquid container and dispenser is adapted to be mounted on the handle 9 at any point along the same but preferably at the

bottom near the mop head for ready manipulation by the foot of the user of the mop. The container is mounted on the handle by means of a bracket 20 comprising a split ring 21, the split ends of which terminate in complementary flattened portions 22 and 23. The portion 22 is formed with an extension 24 which is twisted to a different plane than the plane of the portion 23 as shown in Figures 1 and 5. This twisted extension 24 connects the split ring 21 at the point indicated at 25 to an integral plate portion 26 which is disposed on a plane at right angles to the plane of the body of the split ring, being substantially vertical as viewed in Figure 1 whereas the split ring is substantially horizontal. The plate 26 is provided with spaced holes 27 having restricted notches 28. A bolt 29 passing through openings in the flat portions 22 and 23 of the ring and a wing nut 30 removably clamp the bracket 20 to the handle 9.

The improved container and dispenser is shown as a cylindrical member or can 31 and is preferably made of tinned sheet metal. It may of course be of any desired shape. The can 31 is closed at the bottom by a plate 32 and at the top by a plate 33. Each of these plates is provided with a central opening. Mounted on the plate 32 centrally thereof so as to surround the central opening is a neck or spout member 34. 30 This spout member 34 extends outwardly from the plate 32 and is provided with external and internal screw threads. A similar spout member 35 is provided for the top plate 33. The spout member 34 is covered by a screw threaded cap 36 and the spout 35 by a similar cap member 37.

Positioned inside the spout 35 and screw threaded thereto is an inverted cap member 39 having a small central opening. The upper free 40 edge of cap 39 as viewed in Figure 3 is provided with a plurality of lugs or finger pieces 39a to facilitate insertion and removal of the cap.

Extending through the can 31 centrally thereof and into the spouts 34 and 35 is a rod or 45 shaft 40. A button or foot pedal 41 is threaded on to the top of the shaft 40.

Mounted adjacent the bottom of the can 31 and extending transversely thereof from wall to wall is a channel shaped shelf or bridge member 42 provided with a central opening in alignment with the opening in the inverted cap 39 in spout 35. A helical spring 43 surrounds the shaft 40 near the bottom thereof and has one end bearing on and supported by the bridge member 42 50 55

and its other end fastened to a disk or collar 44 on the shaft 40.

On the lower end of shaft 40 a plate member or disk 45 is fastened which disk is provided with a peripheral rim or flange. Mounted on the inner face of the disk and positioned between the rim thereof is washer 46 of leather, rubber or any suitable material. This washer and disk serve as a valve to close the opening in 10 the neck portion 32a in the bottom plate 32.

The transverse plate portion 36a of the cap 36 at the bottom discharge end of the can is provided with a small opening 36b at a point away from the center of the plate 36a, and pivotally 15 mounted on the outside of said plate portion 36a is another plate or disk 47 provided with a small opening 47a adapted to align with the opening 36b. A lug or finger piece may be formed on the edge of the disk 47 to move the same around as 20 will be understood.

The can 31 may be provided lengthwise thereof with a strip of metal or plate 50 to reinforce the same at said point where rivets 51 with outwardly extending button heads are mounted on 25 the wall of the can. Instead of rivets with outwardly extending button heads, any other outstanding members such as hooks may be mounted on the wall of the can.

In use, the bracket 20 is mounted on the handle 9 as shown in Figure 1. The cap 37 is removed to give access to button 41 and the plate 47 at the bottom is turned so that the openings 36b and 47a are aligned. The can 31 is then mounted on the plate 26 by inserting the button heads 51 in the openings 27 and allowing them to slide down into the notches 28. The can is placed directly over the mop head. Pressure on the button 41 by the foot or hand forces the shaft 40 downwardly against the action of spring 43 and opens the valve comprising disk 45 and washer 46. The oil then flows through the openings 36b and 47a on to the plate 12 and seeps down on to the material 10a.

In using the improved device on a mop or brush of the type shown in Figure 2, the can 31 is mounted on the rear side of the handle 9 so that the wax or oil may drip directly on to the floor and then be spread or rubbed into the floor by the mop head 52.

The cap 37 and closure disk 47 permit the container to be shipped without fear of unwarranted operation of the device or loss of liquid.

Changes in details may be made without departing from the principle of the invention and I desire to be limited only by the state of the prior art and the appended claims.

I claim:

1. A container for liquid comprising a closed member having a filling spout and discharge opening, spring pressed valve means normally closing said discharge opening, a closure cap surrounding said discharge opening and having 10 an opening therein, a disk on the exterior of said closure cap provided with an opening adapted to be moved into alignment with the closure cap opening and manual means normally extending outwardly of said filling spout for operating 15 said valve means to open the discharge opening.

2. A container for liquid comprising a closed member having a filling spout and discharge opening, spring pressed valve means normally closing said discharge opening, a movable shaft 20 extending outwardly of the filling spout for moving said valve means for opening the discharge opening, said filling spout including a tubular neck portion internally and externally 25 screw threaded and a cap member screw threaded to the interior of said neck portion and having its transverse portion positioned inwardly of the neck portion for guiding the movement of the shaft.

3. A container for liquid comprising a closed 30 member having a filling spout and discharge opening, spring pressed valve means normally closing said discharge opening, a movable shaft extending outwardly of the filling spout for moving said valve to open the discharge opening, a closure cap surrounding said discharge opening and valve means and a removable closure cap surrounding the protruding portion of 35 said shaft.

4. A container for liquid comprising a closed 40 member having a filling spout and discharge opening, valve means for closing said discharge opening, a movable shaft for operating said valve means to open the same, spring means for normally keeping the valve closed, a transverse 45 plate for supporting said spring means and for guiding the movement of the shaft near the bottom of the closed member and a member in the filling spout having a transverse plate portion for guiding the movement of said shaft at 50 the top of the cylindrical member.

JAMES FORMAN.
